FIG. 4.

Inventor:

Alice M. Perkins.
By Pearce & Lord, attys.

UNITED STATES PATENT OFFICE.

ALICE M. PERKINS, OF LA CROSSE, WISCONSIN.

LOOPING ATTACHMENT FOR SEWING-MACHINES.

SPECIFICATION forming part of Letters Patent No. 390,896, dated October 9, 1888.

Application filed March 30, 1888. Serial No. 268,958. (No model.)

To all whom it may concern:

Be it known that I, ALICE M. PERKINS, a citizen of the United States, residing at La Crosse, in the county of La Crosse and State of Wisconsin, have invented certain new and useful Improvements in Looping and Tufting Attachments for Sewing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to an attachment for sewing-machines, for making looping, tufting, or fringing; and it consists in the novel construction and combination of the parts, herein-after fully described and claimed.

In the drawings, Figure 1 is a plan view of the attachment from above, showing the looping-hook advanced. Fig. 2 is a similar view showing the looping-hook drawn back. Fig. 3 is a front view of the attachment. Fig. 4 is a longitudinal section taken on line 4-4 in Fig. 1.

A is the foundation-plate of the attachment, provided with the socket *a* and screw *a'*, by means of which it may be secured to the sewing-machine in place of the presser-foot commonly employed.

B is a bracket, which projects upwardly from plate A, and C is a lever pivoted upon the pin *b*, which is screwed into the top of bracket B. The lever C is provided with a vertical slot, *c*, and with a horizontal arm, D, having the slots *d* and *d'* formed through it.

E is the ordinary needle-bar of the sewing-machine, and *e* is a pin which projects from the needle-bar and engages with the slot *d* in the horizontal arm, so that the lever C is caused to vibrate upon its pivot-pin *b*.

F is a plate having a projection, *F'*, on its upper side, which is provided with the pin *f*, engaging with the said slot *e*.

G is a guide-groove for the looping-hook formed in plate A, and *g* indicates projecting lips, which prevent plate F from rising.

H is the looping-hook, which is secured to plate F, and which receives a continuous re-

ciprocating movement from the lever C and the needle-bar.

I is a bracket, also projecting upwardly from plate A, and J is a vertical lever pivoted to the top of bracket I by the pin *i*, and provided with the horizontal curved arm *j*, the end of which projects through the slot *d'* in the horizontal arm of lever C.

K is a plate having the loop-feeding arm M secured to its under side, and *k* are lugs upon the upper side of plate K, with which the rocking lever J may engage at the ends of its stroke. A slot, L, is formed in plate A for the arm M to slide in, and *l* is a plate secured to bracket I for preventing the plate K from rising. The loop-feeding arm M is provided with an extension, *m*, which presses on the yarn while being drawn back by the looping-hook and prevents it from becoming entangled.

N is a bifurcated loop-holding arm secured to plate K on the opposite side of bracket I from the loop-feeding arm M, and *n* is a screw which passes through the fork *n'* on the end of arm N and holds it adjustably secured to plate K.

O is a spring provided with a projection, *o*, which works in a diagonal slot in plate A, and *o'* is a screw for regulating the pressure of the spring. This constitutes a tension device for the yarn.

The operation of the attachment is as follows: The yarn is passed through the diagonal slot under the projection *o* of the spring, and is seized by the looping-hook, which is thrust forward by the upward movement of the needle-bar into the position shown in Figs. 1 and 4. The descent of the needle-bar draws back the hook-forming loop, as shown in Fig. 2. The machine-needle passes through the head of this loop with the descent of the needle-bar and sews it in the usual manner onto a backing of any woven material; or the backing may be dispensed with and the loops of yarn merely sewed together. The needle-bar then rises and the looping-hook is again pushed forward. The loop feeding and holding arms are pushed forward by their actuating-levers when the needle-bar has moved about one-half of its upward stroke, and said arms are drawn back during the second half of the downward stroke.

of the bar, thereby pushing each loop forward as soon as it is disengaged by the needle in its upward stroke and moving out of the way of the yarn when it is being drawn back 5 by the looping-hook during the downstroke of the said needle-bar.

What I claim is—

1. In a looping attachment for a sewing-machine, the combination, with the loop-holding arm arranged substantially in line with the sewing-machine needle, of the loop-feeding arm arranged parallel with the said loop-holding arm, the looping-hook arranged at a right angle to the said holding and feeding arms, 15 and lever mechanism actuated by the needle-bar for reciprocating the said arms and hook, substantially as and for the purpose set forth.

2. In a looping attachment for a sewing-machine, the combination, with the bifurcated 20 loop-holding arm arranged in line with the sewing-machine needle, of the loop-feeding arm arranged parallel with the said loop holding arm, the looping-hook arranged at a right angle to the holding and feeding arms, a vibrating lever operated by the needle-bar for reciprocating the looping-hook and the said holding and feeding arms, and intermediate 25 lever mechanism interposed between the said lever and the loop holding and feeding arms, whereby the said arms are reciprocated intermittently, substantially as and for the purpose set forth.

3. The combination, with the foundation-plate for attachment to the presser-bar of a 35 sewing-machine, and provided with the brackets B and I, of the vibrating lever provided with the vertical slot *c* and horizontal slots *d* and *d'*, the looping-hook having a pin secured thereto engaging with the slot *c*, the loop-40 feeding arm arranged at a right angle to the said hook, and intermediate lever mechanism for intermittently reciprocating the loop-feeding arm and engaging with the said slot *d'*, substantially as and for the purpose set forth.

45 4. The combination, with the foundation-plate provided with brackets B and I, of the looping-hook, the vibrating lever pivoted to bracket B, for reciprocating the hook, the sliding plate K, the loop-feeding and loop-50 holding arms and the lugs secured to the said

plate, the lever pivoted to bracket I and provided with a horizontal arm engaging with a slot in the aforesaid lever, and with a vertical arm engaging the said lugs, whereby an intermittent motion may be imparted to the 55 loop feeding and holding arms, substantially as and for the purpose set forth.

5. In a looping attachment for a sewing-machine, the combination, with the continuously-reciprocating looping-hook, of the intermittently-reciprocating loop holding and feeding arms arranged parallel with each other and at a right angle to the hook, and the adjustable spring provided with a projection upon its under side and bearing upon the yarn 60 in front of the loop-holding arm, substantially as and for the purpose set forth.

6. The combination, with the foundation-plate provided with brackets B and I, of the lever pivoted to bracket B and provided with 70 slots *c*, *d*, and *d'*, the sliding plate provided with a projection, and the pin *f*, engaging with slot *c*, the lips for retaining the plate, the looping-hook secured to the plate and guided in a groove in the foundation-plate, the loop-feeding arm arranged at a right angle to the looping-hook, and intermediate lever mechanism 75 for intermittently reciprocating the loop-feeding arm and engaging with the said slot *d'*, substantially as and for the purpose set forth. 80

7. The combination, with the foundation-plate provided with brackets B and I, of the lever pivoted to bracket I and provided with the horizontal arm *j*, the plate K, provided with lugs *k*, with which the said lever may engage 85 intermittently, the loop feeding and holding arms M and N, secured to plate K, the plate *l*, for keeping the feed-arm M in its guide-groove, the looping-hook at right angles to the feed-arms, and the lever pivoted to bracket B and 90 operatively connected to the looping-hook and to the said horizontal arm *j*, substantially as and for the purpose set forth.

In testimony whereof I affix my signature in presence of two witnesses.

ALICE M. PERKINS.
